UNITED STATES PATENT OFFICE.

WALTER A. KILRAIN AND ANNIE E. KILRAIN, OF CLEVELAND, OHIO, ASSIGNEES, BY
MESNE ASSIGNMENTS, TO JOHN S. PATTERSON, OF PITTSBURGH, PENNSYLVANIA.

SHOE-TREE.

1,149,370.

Specification of Letters Patent. Patented Aug. 10, 1915.

Application filed April 11, 1914. Serial No. 831,303.

To all whom it may concern:

Be it known that we, WALTER A. KILRAIN and ANNIE E. KILRAIN, citizens of the United States, and residents of Cleveland, in the county of Cuyahoga and State of Ohio, have invented a new and useful Improvement in Shoe-Trees; and we do hereby declare the following to be a full, clear, and exact description thereof.

10 Our invention relates to shoe-trees and has special reference to what are known as adjustable shoe-trees.

The object of our invention is to form a cheap, simple and efficient shoe-tree, which 15 can be made adjustable for different lengths of shoes, as well as one which will be adjustable for shoes after they become worn or stretched, and one which can be supported while the shoe is being polished or shined.

To these ends our invention consists, generally stated, in the novel arrangement, construction and combination of parts, as hereinafter more specifically set forth and 25 described and particularly pointed out in the claims.

To enable others skilled in the art to which our invention appertains to construct and use our improved shoe-tree, we will 30 describe the same more fully, referring to the accompanying drawing, in which:—

Figure 1 is a side elevation of our improved shoe-tree showing the same applied to a bracket and in position for use with a 35 shoe. Fig. 2 is a top-plan view of the tree. Fig. 3 is a view of the bracket.

Like symbols of reference herein indicate like parts in each of the figures of the drawing.

40 As illustrated in the drawing 1 represents our improved shoe-tree, which has the usual front part or toe form 2 thereon for insertion in the front part of the shoe and is generally formed of wood or other suitable 45 composition as may be desired.

Removably pivoted in the usual manner within a vertical slot 3 in the front member 2 by the cotter-pin 4, is the shank 5 formed of a thin metal plate, which is positioned 50 vertically and provided with the teeth 6 on its lower edge.

At the rear of the shank-plate 5 are a series of holes 7, to one of which is removably pivoted the adjusting member 8 by means 55 of a cotter-pin 9 passing through such hole,

and this member is provided with the heel portion 10 extending downwardly and outwardly from the same.

Extending upwardly on the member 8 is the handle or arm 11, which is provided 60 with the ears or lugs 12 at its upper end for being adapted to engage with an attaching end *a* dependent on a bracket *b* secured to a wall or other support by means of a wedging dovetailed connection between the 65 said lugs and end when such lugs are caused to engage said end in placing the tree 1 on said bracket by a downward movement of the same.

Mounted on the handle 11 is the adjusting lever 13, which is formed of thin plate metal and in V-shape for extending around the shank-plate 5 by its arms 14, so that the two rear ends 14' on said arms can be pivoted to said handle by the pin 14^a and the 70 other or front end 14" connecting said arms engages with the serrations or teeth 6 on said plate by the rear edge of said end.

Extending across and between the arms 14 on the lever 13 and adjacent the open 80 ends 14' thereon are the lugs 15, which are adapted to form a bearing for one end 16' of a spring rod 16 which is connected at its opposite end to the pivot pin 14^a between said lever and the handle 11, and said rod 85 also extends around said pin on each side of said handle and forms a loop 16" depending therefrom.

When the shoe-tree is desired to be used in a shoe, it will be evident that when the 90 adjusting member 8 is adjusted on the shank 5 for the length of shoe to be applied by the pin 9 in the proper hole 7 in said shank, the front member 2 and heel portion 10 can be positioned in the shoe by pushing down on 95 the handle 11 on the member 8, which will allow the end 14" on the lever 13 to ride over the teeth 6 on the shank so that when the said front member and heel portion have been placed in position in the shoe the tree will 100 be thus held by said end engaging with one of said teeth. When it is desired to polish or shine a shoe thus held by the tree 1, the handle 11 can be readily and quickly connected by its lugs 12 to the end *a* on the 105 bracket *b*, as above described, which will thus suspend said shoe and tree for the polishing or shining operation and enable such operation to be performed conveniently and comfortably, while the tree and shoe can be 110

readily and quickly disengaged from the bracket *b* by raising the same up, so as to free said lugs from said end.

It will thus be seen that our improved 5 shoe tree will be made in such a compact form as will enable its parts to be packed closely together for shipment or transportation by the device being capable of being taken apart and put into a small space. The 10 device is also capable of being attached to a wall or other support, so as to hold the same in a convenient position and ready for use, while it is also capable of being adjustable for different sizes of shoes either when 15 the shoe is in its original or worn shape and when in position in the shoe will be retained in its position by the locking of its parts. The device is also capable of being readily and quickly placed in position in the shoe 20 as described and when it is desired to withdraw the same from the shoe the lever will be capable of being sprung down so as to release it from the shank, so that the device 25 can then be pulled out of the shoe by its handle.

Various modifications and changes in the design and construction of our improved shoe-tree may be resorted to without departing from the spirit of the invention or 30 sacrificing any of its advantages.

What we claim as our invention and desire to secure by Letters Patent is:—

1. A shoe-tree comprising toe and heel members, a shank between said members and 35 pivotally connected to the same, said shank

having serrations on its lower edge, a pawl lever pivotally connected at one end to the heel member and having a bifurcated end surrounding said shank arranged to hold said pawl-lever in a position to insure of its engagement with said serrations, and means for yieldably holding the pawl-lever against the serrations. 40

2. A shoe-tree comprising toe and heel members, a shank between said members and 45 pivotally connected to the same, and a lever having two arms pivotally connected to said heel member, said arms fitting around the shank, and a connection between said arms arranged to engage said shank on its 50 lower edge to hold the tree in position.

3. A shoe-tree comprising toe and heel members, a vertically disposed plate between said members and pivotally connected to the same, said plate having serrations on its 55 lower edge, and a lever having arms pivotally connected to said heel member, said arms fitting around the shank and having a connection at their free ends, said connection being arranged to engage the serrations of the shank to hold the tree in position. 60

In testimony whereof, we the said WALTER A. KILRAIN and ANNIE E. KILRAIN, have hereunto set our hands.

WALTER A. KILRAIN.
ANNIE E. KILRAIN.
